UNITED STATES PATENT OFFICE

2,145,589

PIPE OR TUBE MILL

Stevenson Findlater, McKeesport, Pa., assignor
to National Tube Company, a corporation of
New Jersey

Application June 8, 1937, Serial No. 147,128

3 Claims. (Cl. 80—13)

This invention relates to pipe or tube mills and more particularly to the handling of the mandrel employed therein.

In order to maintain a substantial commercial yield from a pipe or tube mill, the work-piece must be completely rolled in a minimum of time. This, of course, requires the rapid withdrawing and repositioning of the mandrel bar. That is to say, after the work-piece has been rolled and is telescoped over the mandrel bar, the latter must be completely withdrawn from within the work-piece which is then removed from the outlet bed of the mill, after which the mandrel bar is returned to its original position.

On very large mills, for instance those which produce work-pieces of twenty inches in diameter, the mandrel bar and mandrel bar carriage weigh over sixteen thousand pounds and are moved into position at the rate of approximately five hundred feet per minute. When a thin wall work-piece is being produced, the plug on the mandrel bar must be positioned very close to the metal working rolls of the mill, and if permitted to overrun its true position will occasion considerable damage to the metal working rolls and numerous other parts of the mill.

It is among the objects of the present invention to operate a pipe or tube mill in a manner which is not only rapid but which also eliminates damage to the component parts thereof.

Another object is to provide an inexpensive and efficient apparatus which may be installed on pipe or tube mills of existing design to function in the manner previously mentioned.

The foregoing and further objects will be apparent after referring to the drawings, in which:

Figure 1 is a plan of a conventional pipe or tube mill which employs cone-shaped metal-working rolls.

Figure 2 is a plan of the mill of Figure 1 on a smaller scale and disclosing fragmentarily the outlet bed thereof.

Figure 3 is a view similar to Figure 2 but disclosing some of the elements of the pipe or tube mill in a different position.

Figure 4 is a view similar to Figure 1 but disclosing a mandrel bar and the mandrel plug carried thereby in the usual over-run position, which occasions the injurious result previously mentioned.

Figure 5 is a fragmentary plan of a part of the apparatus of the invention.

Figure 6 is a sectional view on the line VI—VI of Figure 7.

Figure 7 is an enlarged view on the line VII—VII of Figure 5.

Figure 8 is a wiring diagram.

Figures 9, 10, 11, 12 and 13 are details of control switches.

Referring more particularly to the drawings, the numerals 2 and 3 designate a pair of cone-shaped metal-working rolls toward which there is extended a compression mandrel bar 4 carrying a mandrel plug 5 which is disposed intermediate the metal-working rolls. After a pipe or tube has been completely rolled between the metal-working rolls 2 and 3, and the intermediate disposed mandrel plug 5, and has moved onto the mandrel bar 4, it is removed from the mill by withdrawing the mandrel bar 4 and mandrel plug 5 and translating the pipe or tube by the usual kick-off arm (not shown), whereupon it is permitted to roll over a conveniently disposed skid-way 6. According to conventional practice, the mandrel bar 4 is suitably attached to a mandrel bar carriage 8 which rides on an elongated frame 9 that forms part of the outlet bed of the mill.

The outlet bed is provided with a pair of substantially spaced grooved pulleys 10 and 11, the latter of which is driven by an adjacently disposed motor 12. A cable 13 is strung between the rollers 10 and 11 and connected at its ends to the mandrel bar carriage 8. Thus, by driving the motor 12, the mandrel bar carriage 8, the mandrel bar 4, and the mandrel plug 5 are moved toward and away from the mill, for the purpose previously mentioned.

Referring to Figure 7, a vertical support 18 is pivoted as at 19 to the outlet bed of the pipe or tube mill adjacent the mandrel bar carriage 8 when the latter is in its forward position.

A laterally extending overhead frame 21 is mounted on the outlet bed of the pipe or tube mill immediate to the rear of the vertical support 18. This laterally extending overhead frame 21 carries a pair of suitably journaled internally threaded sleeves 23 which extend longitudinally over the outlet bed of the mill. Each of these internally threaded sleeves 23 carries a worm gear 24 which is secured thereto. A reversible electric motor 26 is mounted on the laterally extending overhead frame 21 and is connected by means of a suitable coupling 27 to a shaft 28 which extends over and across the internally threaded sleeves 23. A pair of worms 29 are secured to the shaft 28 and engage the worm gears 24 on the internally threaded sleeves 23. The motor 26 is provided with a conventional

magnetic brake 30 for a purpose to be later described.

In each of the internally threaded sleeves 23 there is disposed a forwardly extending screw 32 which is pivotally connected as at 33 to a rearward extension 34 on the vertical support 18.

The upper end of the vertical frame 18 carries a horizontally disposed rotatable shaft 36 which is disposed above the mandrel bar carriage 8 when the latter is in its forward position. This horizontally disposed rotatable shaft 36 has secured thereto a latch 37 having a flattened portion 38 on its extended end. The upper surface of the mandrel bar carriage 8 is provided with an abutment plate 39 having flattened face 40. At one side of the upper end of the vertical support 18 there is disposed a fluid-actuated cylinder 42, the piston of which is pivotally connected, as at 43, to a crank 44 which is secured to the horizontally disposed rotatable shaft 36.

According to the foregoing construction and arrangement of elements, it will be seen that the deenergization of the fluid-actuated cylinder 42 will permit the lowering by gravity of the latch 37 in such manner as to present its flattened surface 38 for contact with the flattened surface 40 on the abutment plate 39 on the mandrel bar carriage 8. When the latch 37 is in this position, the reversible electric motor 26 will be enabled to rotate the internally threaded sleeve 23 to move the screws 32 forwardly and, because of the connection of the latter with the vertical support 18 will move the mandrel bar carriage 8, mandrel bar 4 and mandrel plug 5 toward the metal-working rolls 2 and 3 of the mill.

Any suitable and conventional electric wiring supports including control device, are provided for the motor 26 and magnetic brake 30.

In operation, a tube A, which is shown as having previously been pierced, is introduced between the metal-working rolls 2 and 3 for movement over the mandrel plug 5 on the forward end of the mandrel bar 4. The tube A is moved over the mandrel plug 5 and mandrel bar 4 by the helical advancing action of the metal-working rolls 2 and 3. As soon as the trailing end of the tube A has moved over the mandrel plug 5 and over the mandrel bar 4, the fluid-actuated cylinder 42 is energized to raise the latch 37, and the motor 12 is suitably actuated (automatically or otherwise) to rotate the roller 11 in such manner as to withdraw the mandrel bar carriage 8 along the elongated frame 9 sufficiently to remove the mandrel bar 4 from the interior of the tube A and permit the mandrel plug 5 to drop. The usual kick-off devices (not shown) are then actuated to translate the tube A from the outlet bed of the mill and permit it to roll down the skid-way 6.

After the energization of the fluid-actuated cylinder 42 to raise the latch 37, the magnetic brake 30 and motor 26 are energized, thus permitting the latter to move the vertical support 18 rearwardly a predetermined short distance from the position it previously occupied. As soon as the vertical support 18 has moved this short predetermined rearward distance, the motor 26 and magnetic brake 30 are deenergized, thereby applying the latter. Next, the motor 12 is energized in a direction which is reverse to that previously described, to return the mandrel bar carriage 8 to a position which is proximate but short of its initial position. The fluid-actuated cylinder 42 is then deenergized to lower the latch 37 into contact with the abutment plate 39 on

the mandrel bar carriage 8. The magnetic brake 30 is then energized; and the motor 26 energized in a direction of rotation which is reverse of that previously described. The motor 26 then, through rotation of the internally threaded sleeves 23, moves the vertical support 18 forwardly toward the metal-working rolls 2 and 3 a distance which is sufficient to restore the mandrel bar carriage 8, mandrel bar 4, and mandrel plug 5 to their initial working positions.

The metal-working rolls 2 and 3 are, at this stage of the operation, ready to receive the pipe or tube A and advance the same helically over the mandrel bar 4 and mandrel plug 5 which are now returned to their initial metal-working positions in the manner previously described.

Referring to Figure 8 of the drawings, I have illustrated one form of electrical circuit which may be utilized to operate the devices of the invention in the manner previously described. In this diagram the numerals 100 and 102 designate a pair of suitable power lines carrying normal voltage; such as 220 volts. In order to satisfactorily control the operation of the reversible motor 26, it is connected to the power lines 100 and 102 through a manually operable switch 103 by a line 104 and includes in its circuit contacts 105^a and 105^b, and 106^a and 106^b, which are operated by coils 105 and 106, respectively, in a manner to be later described. The series field of the reversible motor 26 is designated in the line 104 at 26^a. The magnetic brake 30 for the reversible motor 26 is also connected in series in this line 104, whereby it will be energized during the passage of current therethrough.

A line 110 is connected between the power lines 100 and 102 and includes in its circuit contacts 112^a, 114^a and 116^a which form part of limit switches 112, 114 and 116, respectively; together with a coil 106 which operates the contacts 106^a and 106^b of the motor 26. A line 120 is connected to the line 110 between the contact 112^a of the limit switch 112 and the power line 100, and to the line 110 between the coil 106 and the power line 102. This line 120 has included in its circuit contacts 112^b, 114^b and 116^b, which also form part of the limit switches 112, 114 and 116, respectively; together with a coil 105 which operates the contacts 105^a and 105^b of the motor 26.

As shown in Figure 7, the reversible motor 12 which drives the mandrel bar carriage 8 is connected through a reversing switch 125 to a pair of power lines 126 and 127 which provide current of suitable voltage; such as 220 volts.

Referring to Figure 9, the limit switch 112 is shown as comprising an operating arm which is spring-biased as at 112^c into connection with the contact 112^b but operable by contact with the lower part of the mandrel bar carriage 8, while the latter is in its forward position, into connection with the contact 112^a.

The limit switch 114 is shown as comprising an operating arm secured to the shaft 36 on the upper part of the vertical support 18. The energization of the fluid cylinder 42 will move the operating arm of the limit switch 114 into connection with the contact 114^b, and the de-energization of the fluid cylinder 42 will permit the latch 37 on the shaft 36 to drop by gravity and move the operating arm into connection with the contact 114^a.

Referring to Figures 11, 12 and 13 of the drawings, the limit switch 116 is shown as comprising a screw 130 which is secured to and rotates

with the shaft 28. This screw 130 carries a nut 132 which is provided with a centrally depending lug which rides in a guideway 133 formed by part of the laterally extending overhead frame 21. Each side of the nut 132 is provided with a stud 134 which carries a pivotally mounted roller 116. Each of the rollers 116 rides for a limited distance on a longitudinally adjustable contact strip which is mounted on, but suitably insulated from, the laterally extending overhead frame 21. These contact strips form contacts 116^a and 116^b which operate in a manner to be later described. According to the embodiment illustrated, the rollers 116 will, when in extreme positions, connect either the contact 116^a or the contact 116^b, and permit a limited range of travel over the nut 132 during which both contacts will be connected in their respective lines.

While the mandrel bar carriage 8 is in its forward position, the contacts 112^a and 114^a of the limit switches 112 and 114, respectively, are closed, but the nut 132 of the limit switch 116 occupies its extreme inward position on the shaft 130, thereby breaking connection with the contact 116^a but continuing connection with the contact 116^b. Therefore, the operating coil 106 is now deenergized, thereby opening the contacts 106^a and 106^b of the reversible motor 26. The coil 105 is at this time deenergized because the contacts 112^b and 114^b of the limit switches 112 and 114, respectively, are opened. The foregoing position of elements is represented in the diagram of Figure 8 of the drawings.

As soon as the tube A has been completely pierced by the operation of the metal-working rolls 2 and 3 and the mandrel plug 5 on the forward end of the mandrel bar 4, the operator of the mill operates a suitable valve to fill the cylinder 42 with fluid under pressure, thereby raising the latch 37. The raising of the latch 37 breaks the connection of the limit switch 114 with its contact 114^a and makes connection with its contact 114^b. The operator then operates the reversing switch 125 for the reversible motor 12 to drive the same in such manner as to withdraw the mandrel bar carriage 8. This operation of the motor 12 is continued until the mandrel bar carriage 8 is in its extreme rearward position.

As soon as the mandrel bar carriage 8 begins its rearward movement caused by the operation of the reversible motor 12, the contact 112^b of the limit switch 112 is closed by its operating spring 112c. In view of the fact that the limit switches 114 and 116 are at this time already connected with their contacts 114^b and 116^b, respectively, the coil 105 is energized to close the contacts 105^a and 105^b of the motor 26 by the closing of the contact 112^b of the limit switch 112, as just described.

This connection of the motor 26 energizes, and therefore releases, the magnetic brake 30 and permits the former to move the vertical support 18 rearwardly from the position it previously occupied. The extent of the movement is short and determined by the distance required by the travel of the nut 132 to break the connection of the contact 116^b with its contacting roller 116. The breaking of the connection of the limit switch 116 with the contact 116^b deenergizes the coil 105 thereby opening the contacts 105^a and 105^b to deenergize the motor 26 and also the magnetic brake 30 which is then applied.

The foregoing operation of the devices included

in the wiring diagram of Figure 8 is entirely independent of the operation of the reversible motor 12 which, as before stated, is operated to withdraw the mandrel bar carriage 8 to its extreme rearward position, either automatically or manually. When the mandrel bar carriage 8 is completely withdrawn, the reversible motor 12 is deenergized. The operator then operates the usual kick-off arms (not shown) to translate the tube A from the outlet bed of the mill whereupon it is permitted to roll over the skid-way 6. The operator then restores the kick-off arms to their initial positions and operates the reversing switch 125 to drive the reversible motor 12 in such manner as to move the mandrel bar carriage 8 to a position which is proximate, but short of, its initial position. The reversible motor 12 is then deenergized. If desired, the operation of the reversible motor 12 may be regulated by suitable limit switches (not shown).

As soon as the mandrel bar carriage 8 arrives at its proximate initial position, it operates the limit switch 112 to make connection with the contact 112^a and break connection with the contact 112^b. At this time the latch 37 is either already 25 in its lowermost position, or is then moved into such position by exhausting the fluid from the fluid cylinder 42, whereupon it is permitted by gravity to drop. The lowering of the latch 37 operates the limit switch 114 to make connection 30 with the contact 114^a and break connection with the contact 114^b. The limit switches 112 and 116 are already in connection with the contacts 112^a and 116^a, respectively. Therefore, the closing of the contact 114^a of the limit switch 114 35 now energizes the coil 106 which closes the contacts 106^a and 106^b of the reversible motor 26. This energizes the motor 26 and also the magnetic brake 30 which is then released. The motor 26 then moves the vertical support 18 forwardly 40 and, through the latch 37, also the mandrel bar carriage 8. As soon as the mandrel bar carriage 8 is restored to its exactly proper initial position, the now outwardly traveling nut 132 breaks the connection of the limit switch 116 with the contact 116^a but continues its connection with the contact 116^b. The breaking of the connection of the limit switch 116 with the contact 116^a deenergizes the coil 106, thereby opening the contacts 106^a and 106^b to deenergize the motor 26 and 45 also the magnetic brake 30 which is then applied.

The entire apparatus is thus set for another cycle of operation, which is initiated after the passage of a succeeding tube A through the mill.

In my copending application, Serial No. 147,127, 55 entitled "Pipe or tube mill", and filed concurrently herewith, there is disclosed and claimed an apparatus for preventing the direct impact of the mandrel plug with the metal-working rolls of the mills. In said copending application, at least 60 one of the metal-working rolls of the mill is withdrawn from its metal-working position before the mandrel plug is moved into its metal-working position, whereby said mandrel plug cannot make impact against both of said metal-working rolls. That is to say, if the mandrel plug over-runs its metal-working position, it can only make a glancing impact against one of the metal-working rolls. After the mandrel plug has assumed its metal-working position, or an over-run position, the withdrawn metal-working roll is returned to its metal-working position. If desired, both metal-working rolls can, according to said application, be withdrawn prior to the movement of the mandrel plug to its metal-working position, whereby 70 75

a glancing impact of the mandrel plug against even one of the metal-working rolls is prevented.

While I have shown and described one specific embodiment of my invention, it will be understood that I do not wish to be limited exactly thereto, since various modifications may be made without departing from the scope of my invention, as defined by the following claims.

I claim:

- 10 1. A pipe or tube mill comprising, in combination, a plurality of metal-working rolls, a mandrel disposed intermediate said metal-working rolls, releasable means for holding said mandrel in its fixed metal-working position between said metal-working rolls, means for withdrawing said mandrel from said metal-working rolls to permit the removal therefrom of a pipe or tube, means for moving said mandrel to a position adjacent but spaced from its fixed metal-working position, and
- 15 20 means for moving said mandrel into said fixed metal-working position at a decreased rate of speed, said last named means being operable only when said releasable mandrel holding means is in holding position.
- 25 2. A pipe or tube mill comprising, in combination, a plurality of metal-working rolls, a mandrel disposed intermediate said metal-working rolls, releasable means for holding said mandrel

in its fixed metal-working position between said metal-working rolls, means for withdrawing said mandrel from said metal-working rolls to permit the removal therefrom of a pipe or tube, said mandrel withdrawing means being operable by the release of said releasable mandrel holding means, means for moving said mandrel to a position adjacent but spaced from its fixed metal-working position, and means for moving said mandrel into said fixed metal-working position at a decreased rate of speed, said last named means being operable only when said releasable mandrel holding means is in holding position.

3. A pipe or tube mill comprising, in combination, a plurality of metal-working rolls, a mandrel disposed intermediate said metal-working rolls, releasable means for holding said mandrel in its fixed metal-working position between said metal-working rolls, means for withdrawing said mandrel from said metal-working rolls to permit the removal therefrom of a pipe or tube, means for moving said mandrel to a position adjacent but spaced from its initial position, and means for moving said mandrel into said initial position at a decreased rate of speed, said last named means being operable only when said mandrel is adjacent to but spaced from said metal-working rolls.

STEVENSON FINDLATER.
